P. T. DODGE.
TYPOGRAPHICAL MACHINE.
APPLICATION FILED MAR. 4, 1914.

Patented Jan. 26, 1915.

UNITED STATES PATENT OFFICE.

PHILIP T. DODGE, OF NEW YORK, N. Y., ASSIGNOR TO MERGENTHALER LINOTYPE COMPANY, A CORPORATION OF NEW YORK.

TYPOGRAPHICAL MACHINE.

1,126,419.

Specification of Letters Patent. Patented Jan. 26, 1915.

Application filed March 4, 1914. Serial No. 822,279.

To all whom it may concern:

Be it known that I, PHILIP T. DODGE, a citizen of the United States, residing at New York, in the county of New York and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form a 15 slug or linotype against the matrices which produce the type characters thereon, and the matrices thereafter returned through distributing mechanism to the magazine from which they started.

20 The present improvements relate more particularly to the font distinguisher, which is employed to prevent matrices of improper font from being delivered into a magazine. Such mechanism is shown and described in 25 U. S. Letters Patent to D. S. Kennedy, No. 1,080,348, December 2, 1913, wherein the matrices of a given style or size have specially located font indicating notches, and the font distinguisher has a projecting finger 30 similarly located, to permit the passage of corresponding matrices, and to arrest matrices formed with notches in a different position, all as well known in the art. The said Kennedy patent illustrates a style of 35 machine employing a plurality of shiftable magazines, mechanism being also provided in connection therewith, whereby the distinguisher is automatically adjusted to correspond to the magazine in operative position. It often happens that the size or style 40 of matrices in a particular magazine is changed, or that another magazine with different matrices is substituted therefor. The matrices of the font thus substituted are of 45 course formed with differently located notches, and I have therefor devised further means to adapt the distinguisher to these conditions also these means comprising adjustable controlling devices carried directly 50 by the respective magazines.

Obviously many changes and variations

may be made in the embodiment of the invention, and in its mode of application, which will still be comprised within its spirit; and generally speaking, I desire it 50 to be understood that I do not limit myself to any specific form or embodiment, except in so far as such limitations are specified in the claims.

Referring to the drawings: Figure 1 is a 55 side elevation, partly in section, of a portion of a linotype machine with my improvements embodied therein; Fig. 2 is a sectional detail on the line 2—2 of Fig. 1; Fig. 3 is a similar view showing the parts in different 70 position; and Fig. 4 shows matrices belonging to different fonts and illustrating the location of the respective distinguishing notches.

Referring to Fig. 1, the magazines A¹, A², 75 A³, are mounted in the shift frame A¹⁰, and are also detachably arranged; and a font distinguisher B, provided with the projecting finger B¹, is located in the distributor box C; and the matrices X or X¹ are moved so through the box C for distribution, all substantially in the same manner as presented in the Kennedy patent. The font distinguisher B and its finger B¹ are adjustably mounted so as to prevent the passage of a 80 matrix, unless the notch therein corresponds in position to that of the finger. Fig. 4 shows two matrices X and X¹ of different font, and formed with the differently located notches Y and Y¹, it being apparent that if 85 the finger B¹ be set to correspond to the notch of one of these matrices, it will prevent the lateral passage thereover of the other.

The distinguisher B is formed with the 90 button B³, between which and the frame-work is mounted the spring B², so as normally to hold the finger B¹ in its extreme outward position. To effect the automatic adjustment of the distinguisher and its 95 finger to correspond to the particular magazine in operation, I preferably employ the arm E¹ pivotally mounted at E in the frame and formed with the extended portion, E². The portion E² is so shaped and located as 100 to be in the path of the operating abutments G mounted upon the respective magazines A¹, A², A³. As the magazines are moved so as to bring one or another of them into 105 operative position, the corresponding abutment G acts to vary the position of the arm E¹, which is provided with the contact screw 110

B⁴ and the adjusting nut B⁵. The screw B⁴ rests against the end of the distinguisher B, which is therefore moved in one direction by the spring B³, and in the opposite direction by the screw, so as to bring the finger B¹ into proper position to register with the notches of the particular matrices in action.

The parts so far described automatically effect the adjustment of the distinguisher 10 to correspond to the magazine in operation. As previously pointed out, it also happens that from time to time the size or style of the matrices in a particular magazine is changed, or that another magazine with entirely different matrices is substituted therefor, and therefore provision is also made to permit such substitutions, or in other words, so that the font distinguisher will be adjusted to correspond exactly to the notches 15 of any given font. To this end I preferably make the abutments G adjustable, and in the specific form shown they are circular plates eccentrically mounted on the magazines by means of the connected arbors G³ 20 (see also Figs. 2 and 3). Registering holes G¹ are also formed in each of the plates G to engage the pins A²⁰ projecting from the magazines. In the form illustrated, the plate G is laterally movable with relation 25 to the magazine, a spring G⁴ being employed to hold it in its normal operative position and to insure the engagement of one of its holes G¹ with the pin A²⁰, the spring also permitting the outward lateral movement of the plate and its subsequent rotary adjustment 30 to a new position. Each plate is also provided with a knurled head G² to facilitate the desired adjustment. Fig. 2 shows the plate in normal operative position, while Fig. 3 illustrates the manner in which a change of adjustment is effected. The plates G are preferably provided about their perimeters, and in proper relation to the holes G¹, with numerals or other characters to 35 indicate the particular font to which the adjoining portion of the perimeter corresponds, and thereby enable it to be adjusted to correspond to any desired font.

It will be seen that each of the controlling 40 plates is secured directly to the magazine, so that, not only does the shifting of a magazine into operative position properly locate the font distinguisher, but in addition, if a magazine be removed and another one 45 substituted therefor, the font distinguisher may be readily adjusted without the necessity for the adjustment of the other parts and without requiring further attention on the part of the operator, as is necessary in 50 the mechanism presented in the said Kennedy patent. Obviously, such individual controlling means, to correspond to any particular font, could be employed with any

interchangeable magazine, whether the latter be used singly or in connection with a plurality of magazines, as in the specific form illustrated; as in either event, the mere interchange of magazines effects the proper adjustment of the font distinguisher.

Many modifications and variations will 70 suggest themselves to those skilled in the art and still be comprised within the spirit of my invention.

Having thus described my invention, its construction and mode of operation, what 75 I claim and desire to secure by Letters Patent of the United States is as follows:

1. In a typographical machine, the combination of a shift frame, a plurality of magazines removably mounted therein, a font distinguisher, and mechanism for automatically adjusting the font distinguisher to correspond with the magazine in operative position, the said mechanism comprising controlling devices carried directly by the respective magazines so as to be removable therewith and adjustable at will to vary the extent of adjustment of the font distinguisher.

2. In a typographical machine, the combination of a shift frame, a plurality of magazines removably mounted therein, an adjustable font distinguisher, and variant means to control the extent of adjustment of the font distinguisher, and comprising devices carried directly by the respective magazines so as to be removable therewith and adjustable at will to correspond to different fonts of type or matrices in the magazines.

3. In a typographical machine, the combination of a shift frame, a plurality of magazines removably mounted therein, an adjustable font distinguisher, and a plate or member attached to each magazine so as to be removable therewith and adjustable at will to control the adjustment of the font distinguisher.

4. In a typographical machine comprising an adjustable font distinguisher, the combination of a magazine for the type or matrices removably mounted in the machine, and a plate to effect the adjustment of the font distinguisher and carried by the magazine so as to be removable therewith, the said plate being rotatable at will to vary the adjustment of the font distinguisher to correspond to different styles or fonts of type or matrices contained in the magazine.

In testimony whereof I have affixed my 120 signature in presence of two witnesses.

PHILIP T. DODGE.
